TRACTOR CRANE

Ray Charles Hamilton, Marion, Ohio

Application January 20, 1945, Serial No. 573,648

5 Claims.

(Cl. 212—8)

This invention relates to a tractor crane, and more particularly to such a crane adapted to utilize the combination of a conventional form or industrial type tractor plus adapter units, in relation with a crane adapted to be associated therewith.

A primary object of this invention is the provision of an improved tractor crane characterized by increased maneuverability and operating efficiency, wherein power to raise the load of the crane is furnished by a power takeoff attached to and forming a part of the tractor.

An additional object of the invention is the provision of means in association with such a device for raising the boom from horizontal to a desired vertical position, furnished by a hydraulic cylinder adapted to be attached to the tractor frame, the cylinder operating a double drum, to provide an increased operating ratio.

A still further object of the invention is the provision of such a crane, having a turntable associated therewith, mounted on ground caster wheels, wherein rotation of the structure in a horizontal plane is accomplished through the operation of a hydraulic power cylinder mounted on a frame attached to the tractor, and the power adapted to be applied at an angle to turn the turntable throughout a substantial arc of a circle in either direction.

A still further object of the invention is the provision of an improved locking device, adapted rigidly to secure the turntable and fastener in parallel alignment, whereby operation of the tractor, which is provided with a caster-type front wheel, is effective to rotate the complete unit in a full 360 degree circle, the arrangement being such that the front wheel of the tractor and the supporting wheels of the turntable may both move freely to effect such rotation.

Other objects reside in the combinations of elements, arrangement of parts, and features of construction, all as will be more fully pointed out hereinafter and shown in the accompanying drawings wherein there is disclosed a preferred embodiment of this inventive concept.

In the drawings—

Figure 1 is a side elevational view, certain parts thereof being broken away, disclosing a tractor and crane embodying features of the instant inventive concept.

Figure 2 is a top plan view of the unit shown in Figure 1, certain portions thereof being broken away.

Figure 3 is a sectional view taken substantially along the line 3—3 of Figure 2 as viewed in the direction indicated by the arrows.

Figure 4 is a sectional view taken substantially along the line 4—4 of Figure 3 as viewed in the direction indicated by the arrows.

Figure 5 is a fragmentary plan view of a certain constructional detail, and

Figure 6 is an enlarged sectional view taken through one of the hydraulic operating cylinders of the mechanism.

Similar reference characters refer to similar parts throughout the several views of the drawings.

Having reference now to the drawings, there is generally indicated at 10 a tractor, including a motor contained in the customary hood 11, provided with a rear axle 12, at the extremities of which are mounted driving wheels 13. The forward extremity is provided with a projecting member 14, to which is pivotally secured a bracket 15, which supports a wheel 16 of caster type, mounted on an axle 17. A conventional steering rod 18 is provided to govern the movement of the wheel 16.

The axle 12 is provided with a differential mechanism 12' and individual right and left brake pedals 19 and 20, respectively, adapted to be utilized for controlling the movement of the tractor in a manner to be more fully described hereinafter.

A supporting frame or adapter unit in the form of a platform 25 is adapted to be secured to the rear axle 12, as by means of supporting brackets 26, and carries thereon a winch or drum 27, provided with an extending reduced shank 28, and mounted for rotation in brackets 29, carried by the member 25. A cable 30 surrounds the shank portion 28, and extends to an operating rod 31, operatively connected with a hydraulically actuated cylinder 32. As best shown in Figure 6, the cylinder 32 includes an inlet 33 adapted to be provided with a fluid from any desired source, within which is contained a piston 34 adapted to be connected to the operating rod 31.

The rear end of the adapter unit 25 terminates in a concave portion 35 adapted to provide a registering arc of rotation for the arcuate front surface 36 of the base plate 37 of the crane unit, generally indicated at 38. The base plate 37 is mounted on a plurality of caster wheels 39, secured on axles 41 in freely swivelable brackets 40, oppositely disposed transversely of the plate, to which is secured, as on a pivot 43, an extending boom member 44.

A second pair of intermediately positioned brackets 45 has an axle 46 rotatably positioned therebetween, which carries a drum or winch 47.

One end of the axle 46 extends beyond its associated bracket 45 and terminates in a bevel gear 49 adapted to be driven by a bevel gear 50 which is secured to a driveshaft 51 provided with universal joints 52 and 52' and actuated by the power takeoff of the tractor.

The plate 37 is connected to the adapter unit 25 as by means of a bolster 53, secured as by a

ball and socket joint 54 in the plate at one extremity, and fixedly secured as by welding at its opposite end to the adapter member 25.

A pin 60 pivotally mounted in a suitable block in the bolster, as by means of a pivot pin 61, is adapted to engage in a suitable aperture 62, in the front of the plate 37, to secure the plate 37 in the adapter unit, and hence the tractor, in parallel alignment when desired.

Secured beneath the frame of the adapter unit 25, as on a ball and socket member 65, is a hydraulic cylinder 66, similar in internal construction to the hydraulic cylinder 32, and associated with an actuating rod 67, which in turn engages a pin 68 secured to the under side of the plate 37.

The drum 27 has a cable 68 wound thereabout, the upper extremity of which is secured to the upper extremity of the boom 44 (not shown) for raising and lowering the boom, while the drum 47 has wound or reeled thereabout a cable or rope 69, which passes over a suitable pulley (not shown) to the upper extremity of the boom, and terminates in a depending hook or other desired lifting apparatus.

From the foregoing, the operation of the device should now be readily understandable. When it is desired to raise the boom 44 of the tractor, the drum 27 is actuated by means of the hydraulic cylinder 32 through the connection previously described, until the boom is raised to the desired level.

When it is desired to hoist a load on the boom, the drum 47 is energized by the power takeoff of the tractor through the drive shaft 51 to rotate the drum and lift the load.

When a partial rotation of the crane, through the platform or base 37 is desired, up to, illustratively, forty degrees in either direction, rotation of the plate 37 may be effected by energizing the hydraulic cylinder 66, a slot 70 being provided in the forward arcuate edge of the plate 37 for such purpose.

When a greater rotation up to 360 degrees is desired, the tractor 10 may be energized by means of its motor, and a rotation about an effective arc of 360 degrees in either direction effected by controlling the movement of one of the wheels, 13 by means of its associated brake pedals 18 or 19, as desired. The freely rotating caster wheels 39 and 16 are designed to permit rotation about a relatively narrow turning radius.

Obviously, when straight forward movement of the crane is desired in any direction, the same may be effected by movement of the tractor in the conventional manner, towing the crane assembly therebehind.

From the foregoing, it will now be seen that there is herein provided a device accomplishing all of the objects of this invention and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. In a construction of the character described, in combination, a tractor, a caster-type front wheel on said tractor, an adapter unit secured to said tractor and having a concavely arcuate rear extremity, a crane unit including a base plate

having a convexly arcuate extremity adapted rotatably to coact with said rear extremity of said adapter unit, bolster means rotatably securing said crane unit to said adapter unit, a boom on said base plate, a drum on said adapter unit, and means on said tractor to actuate the drum to raise and lower said boom.

2. In a construction of the character described, in combination, a tractor, a caster-type front wheel on said tractor, an adapter unit secured to said tractor and having a concavely arcuate rear extremity, a crane unit including a base plate having a convexly arcuate extremity adapted rotatably to coact with said rear extremity of said adapter unit, bolster means rotatably securing said crane unit to said adapter unit, a boom on said base plate, a drum on said adapter unit, and means on said tractor to actuate the drum to raise and lower said boom, said last-mentioned means including a hydraulic cylinder secured to said tractor.

3. In a construction of the character described, in combination, a tractor, a caster-type front wheel on said tractor, an adapter unit secured to said tractor and having a concavely arcuate rear extremity, a crane unit including a base plate having a convexly arcuate extremity adapted rotatably to coact with said rear extremity of said adapter unit, bolster means rotatably securing said crane unit to said adapter unit, a boom on said base plate, a drum on said adapter unit, means on said tractor to actuate the drum to raise and lower said boom, a second drum on said crane unit adapted to raise and lower a load carried by said boom, and power means on said tractor to rotate said second drum.

4. In a construction of the character described, in combination, a tractor, a caster-type front wheel on said tractor, an adapter unit secured to said tractor and having a concavely arcuate rear extremity, a crane unit including a base plate having a convexly arcuate extremity adapted rotatably to coact with said rear extremity of said adapter unit, bolster means rotatably securing said crane unit to said adapter unit, a boom on said base plate, a drum on said adapter unit, means on said tractor to actuate the drum to raise and lower said boom, a second drum on said crane unit adapted to raise and lower a load carried by said boom, power means on said tractor to rotate said second drum, and a driveshaft connecting said last-mentioned drum and said power unit.

5. In a construction of the character described, in combination, a tractor, a caster-type front wheel on said tractor, an adapter unit secured to said tractor and having a concavely arcuate rear extremity, a crane unit including a base plate having a convexly arcuate extremity adapted rotatably to coact with said rear extremity of said adapter unit, bolster means rotatably securing said crane unit to said adapter unit, a boom on said base plate, a drum on said adapter unit, means on said tractor to actuate the drum to raise and lower said boom, said last-mentioned means including a hydraulic cylinder secured to said tractor, a second drum on said crane unit adapted to raise and lower the load on said boom, power means on said tractor to rotate said second drum, and a driveshaft connecting said last-mentioned drum and said power means.

RAY CHARLES HAMILTON.
